UNITED STATES PATENT OFFICE.

CHARLES P. MINGST, OF EVANSVILLE, INDIANA.

CARBURETER FOR HYDROCARBON-ENGINES.

SPECIFICATION forming part of Letters Patent No. 790,379, dated May 23, 1905.

Application filed February 24, 1904. Serial No. 195,083.

To all whom it may concern:

Be it known that I, CHARLES P. MINGST, a citizen of the United States, residing at Evansville, county of Vanderburg, and State of Indiana, have invented certain new and useful Improvements in Carbureters for Hydrocarbon-Engines, of which the following is a specification.

This invention relates to carbureters for hydrocarbon-engines such as are used on automobiles and other self-propelled vehicles.

The object of the present invention is the provision of a carbureter which will be of compact form and entirely self-contained—that is, so arranged that the chamber for holding the gasoline or hydrocarbon fluid and the mixing-chamber, wherein the air and gasoline are mixed, will be contained one within the other and all outside communicating pipes, ducts, and other parts will be dispensed with.

Another object of the invention is the provision, in a carbureter, of a novel form of air-intake and means for controlling the same.

The invention has for a further object the provision of a novel arrangement of float and valve, the latter on the removable cover to the gasoline-chamber, whereby the float is prevented from tilting and the gasoline is kept at the proper level at all times regardless of tilting of the carbureter when used on an automobile, and provision is made for rapid removal of the valve, with the cover, for inspection of the interior of the gasoline-chamber.

The invention contemplates provision of other features and novel constructions and combinations of parts, all as set forth fully hereinafter, while the novel features are recited in the appended claims.

In the accompanying drawings, Figure 1 is a sectional elevation of the complete carbureter; Fig. 2, a section on line 2 2 of Fig. 1, and Fig. 3 a section on line 3 3 of Fig. 1.

The gasoline-chamber 1 is in the form of an annulus having the central tubular mixing-chamber 2, provided with screw-threads 3, on which the circular cover 4 screws down on the chamber 1. Threaded into the cover 4 is a coupling or union 5, which is connected to the gasoline-tank and has a valve-seat 6 and a valve-chamber 7, a ball-valve 8 being adapted

to close the seat 6 when pressed thereagainst by a valve-closer 9, which consists of an upright stem slidable through a bushing 11 in the lower end of the coupling 5 and provided with a head 12, movable in the chamber 7 and 55 arranged to engage the ball-valve 8. When the stem is down, the ball-valve 8 is off the seat 6. Pivoted at 9' to lugs 4', depending from cover 4, is a lever 13, which has a semi-circular fork, as more clearly seen in Fig. 2, 60 which rests upon an annular float 14, supported on the gasoline 15 in the gasoline-chamber 1. The valve-closer rests on the lever 13, and when the fluid is at the proper level the float, through the medium of the lever, holds 65 the valve-closer up against the ball-valve and cuts off the supply of gasoline; but when the supply of gasoline becomes too low the ball-valve is unseated and an additional supply of gasoline is discharged into the chamber 1, and 70 the valve is then automatically closed by the float. Tilting of the carbureter or jarring it when used on an automobile is compensated for by the provision of the automatic valve mechanism before described to prevent unnecessary additions of gasoline to the chamber, and the provision of the fork of lever 13 prevents the float from tilting up on the side opposite where the stem bears on the float, thus 75 insuring reliability of action. 8c

Within the mixing-chamber 2 is the needle-valve casing 15', which is joined to the chamber 1 by the diametrically-disposed conduits or pipes 16 and 17, which take in the gasoline from both sides of the chamber 1, and thus 85 insure a proper feed to the needle-valve casing 15' at all times, and by positioning these pipes within the mixing-chamber 1 thereby obtain a marked advantage over other carbureters which have the pipes or ducts on the 90 outside of the device, where they are liable to injury, and by the provision of my construction a more compact and a self-contained arrangement is had. The needle-valve 18 has a suitable hand-wheel 19 and passes 95 through the usual bonnet 20, whereby the supply of gasoline to the mixing-chamber can be regulated. The air-intake consists of the open end 21 of the mixing-chamber 2. Slidable on the needle-valve casing 15 is a throt- 100

tle seat-valve 22, which is normally held off the air-intake 21 by a spring 23. A lever 24, pivoted to the chamber 1 at 25, coöperates with the throttle-valve to regulate the feed 5 of the air to the interior of the mixing-chamber 2.

It will be understood that the supply of air and gasolene to the mixing-chamber is regulated to suit the conditions of use by means 10 of the needle-valve, and the lever and the float and supply-valve automatically take care of the feed of the gasolene to the chamber.

Having thus described my invention, what I claim as new, and desire to secure by Letters 15 Patent, is—

1. In a carbureter, the combination with a fluid-chamber and a mixing-chamber contained therein, of a needle-valve casing within the mixing-chamber and in communication 20 with the fluid-chamber, a needle-valve for said

needle-valve casing, a throttle-valve for the air-intake which is slidable on the needle-valve casing, and means for regulating the throttle-valve.

2. In a carbureter, the combination with a 25 hydrocarbon-fluid chamber and a mixing-chamber, of an air-intake for the mixing-chamber, a regulable valve controlling said air-intake, a spring normally keeping said valve unseated, and means for regulating the 30 position of the valve in opposition to the action of the spring to increase or diminish the throttling of the air.

In testimony whereof I hereunto affix my signature in presence of two witnesses.

CHARLES P. MINGST.
